UNITED STATES PATENT OFFICE.

ABRAM E. SMITH, OF BROOKLYN, NEW YORK.

RAILWAY-CAR-TRUCK BOLSTER.

1,073,178.

Specification of Letters Patent. Patented Sept. 16, 1913.

Application filed August 14, 1908. Serial No. 443,625.

To all whom it may concern:

Be it known that I, ABRAM E. SMITH, a citizen of the United States, residing in Brooklyn, county of Kings, State of New York, have invented certain new and useful Improvements in Railway-Car-Truck Bolsters; and I do declare the following to be a full, clear, and exact description of the invention, reference being had to the accompanying drawing, forming a part of this specification, such as will enable others skilled in the art to which it appertains to make and use same.

This invention relates to an improved cast railway car truck bolster.

The object of the invention is to provide a casting which will have the maximum strength in all of the component parts of the section, as the strains are eliminated in the manufacture, due to the large openings in top of said casting and to the heavy section being confined to the bottom member only, the balance of the section being uniform throughout which permits uniformity in cooling.

Another object of the invention is the use of a casting (which is the railway car bolster proper) in combination with a rolled plate which performs the functions of a compression member and ties the sides of said casting together.

In the accompanying drawing Figure I represents a perspective view of this railway car bolster assembled; Fig. II a cross sectional view at the center.

In the embodiment herein illustrated are three members, namely, the body 1 of the bolster, a top plate 2, and a center plate 3, which, when the members are assembled, 40 form a complete railway car bolster ready for its intended service.

Member 1 consists of a hollow casting which is the bolster proper, of a uniform trapezoidal section with large openings in

the top of said casting which permit same to cool uniformly when same is being manufactured. Said casting has two flanges projecting outward from sides for the purpose of securing top plate and center plate to said casting. The center plate support and side 50 bearings are cast integral with the casting.

Member 2 is a rolled plate which when applied to the casting performs the functions of a compression member and ties the sides of the casting together. 55

Member 3 is a conventional type of truck center plate.

I claim as my invention—

1. A car truck bolster made of a hollow casting in combination with a rolled plate 60 which performs the function of a compression member and ties the sides of the bolster together.

2. A cast car truck bolster with side bearings and center plate support cast integral 65 with the bolster proper and a rolled plate and center plate applied to top of casting.

3. A car truck bolster, composed of a hollow casting with, first, parallel upright sides of uniform thickness interconnecting the top 70 and bottom of the bolster; second, a top of like uniform thickness cut away over the larger part of the spaces which extend longitudinally between the center bearing and the side bearings and transversely between 75 the sides of the bolster; third, flanges forming part of the top of the bolster which project beyond the sides of the bolster and are adapted for the attachment thereto of a top plate, and, fourth, a bottom of greater 80 thickness than said sides and top.

In testimony whereof, I have hereunto set my hand, this 4th day of August 1908.

ABRAM E. SMITH.
